PIPE AND TOOL JOINT

Rawley D. Haas, Gaffney, S. C.

Application October 18, 1938, Serial No. 235,691

1 Claim. (Cl. 287—125)

This invention relates to improvements in threaded joints, and it is more particularly concerned with such joints as used in oil well drilling. Persons acquainted with this art know that the loads imposed upon pipe and tool joints in making up a casing and tool string reach tremendous proportions.

It is a common occurrence that the load on the uppermost threads will run into the hundreds of thousands of pounds and obviously, there is always the danger of the threads collapsing by stripping completely out of the joint. This danger is more likely to occur in the tool string than in the casing string, and for that reason the invention is herein disclosed as related to a pin and box of a tool string. But it is to be understood that the identical principle is applicable to the joints of a casing string.

Efforts have been made heretofore to improve upon the commonly employed V or square threads by shaping the threads so that a longitudinal section through the joint makes them look somewhat like the teeth of a saw. While the top of each modified thread has been given a downward and outward pitch, yet the bottom of the thread has been made either straight (perpendicular to the axis of the pipe or tool joint) or given a slight downward pitch towards said axis. The two latter arrangements have not been found as effectual as desired, for which reason the instant improvement has been devised with the following objects:

First, to provide a thread construction for a tool joint, capable of actually drawing the pin and box together upon the ultimate tightening of the latter.

Second, to insure the sealing off of the circulation of fluid through the thread passages of the tool (or pipe) joint, said sealing off function becoming increasingly more effective as the load on the thread increases.

Third, to provide a tool joint having a thread of which both sides are pitched in the same general direction toward the axis of said tool joint.

Other objects and advantages will appear in the following specification, reference being had to the accompanying drawing, in which:

Figure 1 is a central vertical section of a tool joint, the thread on the pin and in the box being constructed in accordance with the invention.

Figure 2 is an enlarged section of a portion of the thread illustrating how the top and bottom are pitched in the same general direction as the axis of the tool joint.

Figure 3 is a sectional view illustrating the seal-

ing effect of the thread when subjected to a heavy load.

Figure 4 is a detail sectional view illustrating the principle of the invention embodied in a sharp thread rather than a blunt one, as in Figs. 1, 2 and 3.

In Fig. 1 the tool joint 1 comprises the pin 2 and box 3. Each of these elements is part of a rod section, only the rod section 4 of the pin being partially shown.

It is observed in Fig. 1 that the pin 2 is of tapering form, as distinguished from the more commonly known type of straight-side pins in tool joints. This taper of the pin is known to afford a greater strength in making the joint than if it were of cylindrical form. The extremity of the pin has a conical depression 5 in which a conical dependency 6 in the box 3 is seated when the pin is screwed in to the limit. This interengaging conical formation locks the inner end of the pin against any possibility whatever of vibrating in the lateral direction and this is a large contribution toward keeping the pin and box screwed tight. If lateral vibration could occur, as it does in an instance wherein a conical formation such as shown is not provided, said vibration even though minute will cause the threads to ultimately loosen.

At this point it is desired to state that the pin 2 is either solid in actual practice as shown, or provided with a central, longitudinal bore in communication with a similar bore through the box. In either case the conical configuration 5, 6, between the male and female members has the effect stated, namely, of locking the two together. This is accomplished by the cam action between the confronting and contacting surfaces, which draws the box or female member in toward the pin or male member.

Another important effect of the tapering pin 2 is the provision of a wide thread base 7. This affords strength where it is most needed. Particular attention is directed to the thread itself, the particular cross sectional shape shown constituting the underlying invention. The thread 8 on the pin 2 is adapted to be screwed into the thread passage 9 in the box 3. The top 10 of the thread 8 is set at a pitch to the axis 11 of the tool joint, said pitch being upward as denoted by the pitch line 12 (Fig. 2).

The bottom of the thread 8 is also set at a pitch to the axis 11, the direction of the pitch also being upward as denoted by the pitch line 14. But the pitch 14 is slight as compared to the pitch 12. The crest 15 of the thread 8 is made blunt (Fig.

2), this particular configuration being best adapted for rough work. But in Fig. 4 the crest 16 is made sharp, the principle of pitching the top 10a and bottom 13a in the same general upward direction toward the axis of the pin being preserved.

By virtue of having the short side or bottom of the thread on the slight incline shown, there is a strong tendency to pull the pin and box together because of the interengaged hook form of the thread in the box or female member and undercut form of the thread on the pin or male member. The bottom 13, which stands on a slight upward inclination, yet considered as a part of the thread 8, rests and rides upon the companion thread 17 of the box, the top 18 of which stands at an outward decline. This riding together of these matching surfaces has the effect of drawing the box 3 inwardly toward the pin when the two are screwed together. The action is that of a cam, and the result is an extremely tight interconnection.

Reference is now made to Fig. 3. The direction of the load is indicated by the arrow *a*. The full and dotted line positions of the thread 8 are greatly exaggerated. As the load increases there is a tendency toward a slight clockwise turning of the thread in the direction of arrow *b*. The crest 15 is thus projected outwardly an extremely small distance (arrow *c*), thus tending to flatten the bottom 13 of the thread. The seal-

ing function thus improves with the increase in the load, the bending of the threads resulting in their jamming together more and more tightly, progressively securing against leaks.

But by the time that this flattening has occurred the tool joint will be under an extremely heavy load. The effect of this clockwise turning of the thread is to jam the crest 15 even more tightly into the thread passage 9 than before, thus sealing the thread passage against any possibility of fluid entering it.

I claim:

A coupling for use in connecting a pair of members adapted to sustain a ponderous load, said coupling consisting of male and female members having matching threads, said threads having short sides inclined slightly downwardly from a perpendicular to the axis of the coupling, thereby to define a hook-form of the threads on the female member and an undercut form on the threads of the male member, said thread configurations exercising a cam action under pressure of the load sustained by the male member to draw said members together and establish a sealing-off function, the tops of the male threads and the corresponding portions of the female threads being pitched sharply downward in respect to said perpendicular to the coupling axis to act as a brace.
